(57) **CLAIM**

The ornamental design for article of jewelry, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of an article of jewelry showing my new design in a fluoresced state;

FIG. 2 is a front elevation view thereof, the rear elevation view being a mirror image thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof, showing the article of jewelry in an unfluoresced state.

The short dash-short dash lines illustrate portions of the article of jewelry that form no part of the claimed design. The subject matter in this patent includes a process or period in which the appearance of the design changes. This process or period forms no part of the claimed design.
